UNITED STATES PATENT OFFICE

ARTHUR J. LANDRY, OF EAST BOSTON, MASSACHUSETTS

FLOAT FOR SUPPORTING FIRE HOSE NOZZLES

Application filed July 25, 1930. Serial No. 470,579.

This invention relates to fire fighting apparatus and particularly to devices for fighting fires in locations which are rendered inaccessible by reason of a closely adjacent body 5 of water. It has been the experience of fire fighting organizations in general that in certain types of fires the apparatus with which they are equipped is entirely inadequate to save the property which in the ordinary fire 10 could be saved. Where fire occurs in buildings, wharfs, bridges and other property situated above or closely adjacent to a body of water there have been instances where a great deal of property was destroyed which might 15 have been saved by the use of proper equipment. In large coastwise cities and towns a great deal of property is jeopardized by inadequate means for fighting fires occurring in situations such as those above pointed out. 20 It is the general object of this invention to provide a means to fight fires in inaccessible locations above and closely adjacent a body of water.

A further object of the invention is to provide 25 a fire fighting device which supports a nozzle upon the surface of a body of water having means operable to control the position of the nozzle from a remote point.

A further object of the invention is to provide 30 a device which will project a stream of fire extinguishing fluid upwardly against a burning object near the surface of the water and in such a restricted position that a small boat carrying men and equipment could not be navigated.

A further object of the invention is to provide 35 a mobile nozzle provided with a floating support which may be connected to the main pumping system of a fire boat or land-pumping engine and controlled from a point of safety at a distance remote from the nozzle.

A further object of the invention is to provide 40 a fire fighting device of the construction above suggested having a remote controlling means which is extensible.

A further object of the invention is to provide 45 a remotely controlled nozzle having a floating support and a rigid remote controlled device connected thereto from which

a standard hose is supported in a submerged position with the exception of a short section near the support thereby protecting the hose from the heat of the fire.

Other objects and features will more fully 50 appear from the following description in connection with the accompanying drawings, and will be particularly pointed out in the claims.

The device consists primarily of a shallow 55 float of small dimensions which acts to support a nozzle of any desired type. A hose line preferably of standard construction connects the nozzle with the means which supplies the fire extinguishing fluid. Such 60 means may be a fire boat or under certain conditions the device may be used in shallow water in conjunction with a land-pumping engine.

The float with its nozzle is maneuvered 65 into position and thereafter controlled from a remote point by means of a rigid arm connected to the float. The arm is desirably composed of a plurality of detachable sections 70 thereby permitting it to be extended 75 to the required distance from the point where it is to be operated.

In the drawings:

Fig. 1 is a plan view of the preferred form 80 of the device.

Fig. 2 is a side elevation of the device.

Fig. 3 illustrates the manner in which 85 the device may be used to fight a fire from beneath a structure which is closely adjacent to the surface of a body of water.

Fig. 4 is a cross section on line 4—4 Fig. 5.

Fig. 5 is a cross section on line 5—5 Fig. 4.

Fig. 6 is a perspective view illustrating the device in operative position.

In fighting fires where it has been necessary 90 to play a stream of fluid under a wharf, dock or other structure of similar nature above a body of water it has been necessary to navigate a small boat containing men and an independent pumping unit under the structure. 95 Such procedure has been found inadequate to cope with anything but a very small blaze, and furthermore subjects the crew of the boat to extreme danger. The most highly restricting feature of such practice, however, 100

is the fact that a substantial amount of space must exist in which to maneuver the boat. In many situations the available space below the structure prohibits the use of such equipment in which case the situation is hopeless.

6 There are on record many fires where enormous loss has occurred in the situation such as that above pointed out. It is freely acknowledged that if suitable equipment had been available the loss in such case would 10 have been relatively small. The present invention supplies the means with which a powerful jet of fire extinguishing fluid may be projected upwardly against burning objects which are situated in inaccessible locations close to the surface of a body of water.

15 The size of the float or pontoon employed to support the nozzle may be relatively small. The buoyancy required of the float is merely sufficient to support the reaction of the nozzle 20 at maximum pressure plus the weight due to the various parts attached thereto. It has been found, therefore, that the float may be constructed of a size sufficiently small to enter the most restricted locations. A further very important feature of the device 25 is its ability to deliver the maximum volume of fluid to exactly the required point without endangering the life and limb of the fireman.

30 In the preferred construction illustrated a shallow float or pontoon 1 is constructed of any suitable material preferably sheet metal. The pontoon may be of a relatively long narrow, rectangular or oval shape. A thoroughly practical form for the pontoon is herein shown which is circular in plan view and conical on its upper surface. At the top of the conical portion 2 a hollow fitting 3 is secured by means of the ears 4 to the float. The hollow fitting 3 functions as a 90° elbow 40 to direct the fluid fed thereto in a horizontal direction upwardly in a substantially vertical direction. The horizontal portion 5 of the fitting 3 is provided with a threaded connection to receive the end of a standard hose coupling 6 at the end of a hose line 7 which communicates with the fluid-supplying means. The vertical portion of the hollow fitting 3 is 45 provided with male screw threads to receive a nozzle 8. The nozzle may be of any desired type or the device may operate without a nozzle. The particular nozzle shown is of the rotary type having a rotating head 9 by means 50 of which the fluid is spread throughout a considerable area. Any other suitable arrangement of float and nozzle may be employed 55 however.

60 Means are provided to manipulate the float from a remote point. A desirable method of accomplishing this result is herein illustrated. A rigid arm 10 preferably formed of detachable sections is secured at one end to the float and is operable at its other end to control the 65 movement of the float and thus direct the

stream of water into the most effective position. The arm 10 may be rigidly attached to the float or secured thereto in any desirable manner. As shown, the arm is flexibly connected to the float 1 by means of a U shape 70 bail member 11, the two legs of which are provided with eyeleted ends 12 which are connected to eye-bolts 13 fixed near the periphery of the float at diagonally opposite points thereof. The bail member 11 is provided with a socket 14 at substantially the mid-point between the two legs thereof. The socket 14 is adapted to receive one end of the first of the sections 15 of which the arm 10 is composed. The other end of the sections 15 75 are provided with sockets 16 to receive the ends of the succeeding sections of the arm. By assembling a plurality of sections the arm may be extended to the desired length.

80 The sections 15 are constructed of hollow metal tubing preferably square in cross section. A method will be hereinafter described in detail by means of which the arm 10 is used to tip the float out of its normally vertical position by rotating it about its longitudinal axis. The square cross sectional shape of the sections 15 is readily adapted to the formation of firm unyielding joints between the sections so that when the arm is assembled it will be sufficiently rigid to give the operator of the 85 device complete control over the float. The sections 15 may be constructed of short lengths of standard square tubing upon one end of which is secured a short piece of tubing 17 of a size to loosely fit over one end of each section. The tubing 17 is telescoped 90 upon the end of the tube 15 for substantially one-half of its length, and is welded thereto as at 18 or otherwise secured to the tubing 15. The projecting end of the tube 17 then constitutes the socket 16 into which the end of the 95 next section is fitted.

To secure the sections 15 of the arm 10 together a plurality of pins 19 are projected 100 through apertures 20 in the tubes 17 and also through registering apertures 21 in the ends of the tube sections 15. The pins 19 are provided with heads 22 at one end and at their other ends which project through and beyond the tubing 17 rectangular openings 23 105 are formed in which are received especially constructed keys 24. The end section 25 of each key is of a size to readily pass through the aperture 23 while the middle section 110 thereof 26 is slightly less in height than that of the section 25 while the third section 27 will not pass through the aperture. A small coil spring 28 is placed under the heads 22 115 of the pins and bears against the tubing 17. To assemble the sections of the arm 10 the small ends thereof are fitted into the sockets 16 of the adjacent sections. The pins 19 are 120 then thrust into the registering apertures of the two adjacent sections until the coil spring 125 is compressed slightly, at which time the 130

apertures 23 are free to receive the keys 24 which are inserted therein until the aperture 23 embraces the middle section 26 thereof after which the springs 28 are allowed to expand bringing the upper face 29 of the aperture 23 against the upper edge of the section 26 of the key thus locking the key and the pins securely in position. To further insure the locked condition of the sections 10 a hole may be drilled in the section 25 of the keys to receive cotter pins 30. To disengage one section from the other the cotter pins 30 are first removed after which the springs 28 are slightly compressed until the keys 24 15 can be removed. Upon removing the keys the pins 19 are in turn removed to permit the sections to be parted.

In fighting fires time is an essential element to be considered. It is desirable, therefore, that the locking pins 19 and the keys 24 be always available to quickly assemble the sections of the arm. The pins 19 therefore are permanently attached to the entering ends 31 of the sections 15 by a short length 25 of chain 32 while the key 24 is attached to the tube section 17 by means of the chain 33.

The device may be used in shallow water in connection with land pumping engines, but its most important use is in connection with a fire boat of standard design in which case the float may be launched directly from the side of a fire boat 34 or as shown in Figs. 3 and 4 from the side of a small boat 35. In either case the connecting hose line 7 is attached to the pumping system of the fire boat. To put the apparatus into action the float with its nozzle and connecting hose line is launched upon the surface of the water and section after section is added to the arm during which time the hose line is paid out until the required distance is reached. One or more of the floats may be used. As shown in Fig. 4 three are in operation each having an independent hose connection leading to the pumps of the fire boat.

It is possible for a man to maneuver the floats by grasping the end of the rigid arm 10. It is possible, however, to control the floats by other means. The force of reaction of the nozzle when it is in operation may be employed to move the float. This is accomplished by twisting the end of the arm 10 sufficiently to tip the nozzle slightly away from its vertical position. An ordinary wrench of any desired type may be directly applied to the end of the arm 10 to accomplish this result. For this purpose, however, a special wrench 36 desirably is employed. The socket portion 37 of the wrench is of the proper size to fit snugly over the end of the square tubing. The wrench is provided with two handle extensions 38 which are adapted to be grasped by the operator thus enabling him to apply sufficient twist to the arm to tip the float into an angular position. When

in this position a component of the force of reaction tends to move the float substantially laterally of the arm 10 which results in swinging the float about an arc of which the operating point is a center. Thus the reaction of the nozzle is employed to shift the position thereof at the will of the operator.

The hose line 7 is desirably supported from the arm 10 by means of short sections of chain 39 fixed at one end to the sections 15 and provided at its other end with a quick detachable connection 40. To support the hose line the chains 39 are looped around the hose and fastened to the arm sections 15 by means of the detachable connection 38. The chains 39 are preferably of such a length that the hose line will be suspended beneath the surface of the body of water from which the device is operating thereby protecting it from the heat of nearby burning objects.

A very efficient means is thus provided for fighting fires under docks, bridges and similar structures where the available space prohibits the use of existing equipment. One particular instance where such apparatus is indispensable is in fighting a fire on a wooden bridge where the roadbed is paved with non-inflammable material such as concrete or cobblestones thus rendering attack from the upper surface absolutely ineffective. Such fires can be readily attacked from below by means of the present invention.

Having thus described the invention, what is claimed as new, and desired to be secured by Letters Patent, is:

1. Fire fighting apparatus comprising a mobile float, a conduit supported at one end on the float and connected at its other end to a supply of fire extinguishing fluid, said conduit having an opening at the float positioned to project the fluid upwardly and means connected to the float operable to control the position thereof from a remote point.

2. Fire fighting apparatus comprising a mobile float, a nozzle supported thereon operable to project one or more jets of fire extinguishing fluid upwardly therefrom, a conduit connecting the nozzle with a supply of fluid and means connected to the float including a rigid member operable to control the position of the float from a remote point.

3. Fire fighting apparatus comprising a shallow mobile float adapted to be supported by a body of water, a nozzle supported thereon near the surface of the water which buoys the float said nozzle positioned to discharge a stream of fluid upwardly, a hose line connecting the nozzle with a supply of fire extinguishing fluid, an arm connected at one end to the float and operable at a point remote therefrom to control the position thereof whereby a stream of fluid may be projected upwardly in inaccessible locations above the surface of a body of water.

4. Fire fighting apparatus comprising a

5 project the fluid upwardly from the float and a rigid arm connected to the float having sections detachably joined together by means of which the length of the arm may be varied, said arm being operable to control the movement of the float at a remote point therefrom determined by the length of the arm.

6. Fire fighting apparatus comprising a shallow mobile float, a conduit mounted on said float and connected to a supply of fire extinguishing fluid, a nozzle supported by the float connected to said conduit and operable to project the fluid upwardly, a rigid arm connected to the float operable to control the position thereof at a point remote therefrom and means acting to support said conduit from the rigid arm.

15 7. Fire fighting apparatus comprising a shallow mobile float, a conduit mounted on said float and communicating with a supply of fire extinguishing fluid, a nozzle supported on said float connected with said conduit and operable to project the fluid upwardly, a rigid arm formed of detachable sections flexibly connected to the float operable to control the position thereof at a point remote therefrom and means acting to support said conduit from the rigid arm.

20 8. In combination with means to supply fire quenching fluid under pressure, an apparatus comprising a mobile float, a conduit supported at one end thereby connected to the supply of fire extinguishing fluid and having one or more outlets at the float operable to direct said fluid upwardly therefrom and a rigid arm formed of detachable sections connected at one end to the float operable to control the movement thereof at a distance therefrom determined by the length of the arm.

25 9. Fire fighting apparatus comprising a shallow mobile float adaptable to be supported by a body of water, a nozzle supported thereon operable to project a stream of fluid upwardly, a conduit connecting the nozzle with a supply of fire extinguishing fluid, a rigid arm connected to the float operable to control the position thereof at a point remote therefrom and means acting to support said conduit from said rigid arm below the surface of the body of water on which the float rests whereby fluid may be projected against burning objects in inaccessible places above the surface of the said body of water and the conduit protected from the heat of the fire.

30 10. Fire fighting apparatus comprising a shallow mobile float, a conduit mounted on said float and connected to a supply of fire extinguishing fluid, a nozzle supported by the float connected to said conduit and arranged to project the fluid upwardly, a rigid arm connected to the float and means con-
